(57) **CLAIM**

The ornamental design for a release mechanism knob for a
waste container, as shown and described.

DESCRIPTION

FIG. 1 is a top, front, right side perspective view of a release
mechanism knob for a waste container showing my new
design.

FIG. 2 is a bottom, back, right side perspective view thereof.

FIG. 3 is a top, back, left side perspective view thereof.

FIG. 4 is a bottom, front, left side perspective view thereof.

FIG. 5 is a top view thereof.

FIG. 6 is a bottom view thereof.

FIG. 7 is a front view thereof.

FIG. 8 is a back view thereof.

FIG. 9 is a right side view thereof; and,

FIG. 10 is a left side view thereof.

The broken lines shown represent unclaimed subject matter
and form no part of the claimed design.
